UNITED STATES PATENT OFFICE.

JOSEPH J. NENNO, OF OLEAN, NEW YORK.

DESIGN FOR A DISPLAY-RACK.

44,539.

Specification for Design.

Patented Aug. 19, 1913.

Application filed May 29, 1913. Serial No. 770,799. Term of patent 7 years.

To all whom it may concern:

Be it known that I, JOSEPH J. NENNO, a citizen of the United States, residing at Olean, in the county of Cattaraugus and State of New York, have invented a new, original, and ornamental Design for a Display-Rack, of which the following is a specification.

Reference is had to the accompanying drawing, in which: The figure is a perspective view of a display rack, showing my new and ornamental design.

The display rack is composed of a vertical series of horizontal sections 1, arranged in alinement and having spaced parallel longitudinally disposed shelves 2 increasing in length from the sides of the sections and connected at their terminals by V-shaped end bars 3, having converging sides tapered outwardly. The sections 1 are tapered at

each end, and they are connected at the angles or apexes of the V-shaped end bars by upright bars 4, forming an oppositely tapered display rack. Each end of the display rack presents an outward taper with respect to the sections and an inward taper with respect to the V-shaped end bars. The display rack is open at the sides and ends of the shelves.

I claim:—

The ornamental design for a display rack, as shown and described.

In testimony, that I claim the foregoing as my own, I have hereto affixed my signature in the presence of two witnesses.

JOSEPH J. NENNO.

Witnesses:

CARL SCHÜTULE,
S. T. HELE.
